(57) **CLAIM**

The ornamental design for a laundry cart plastic disposable liner, as shown and described.

DESCRIPTION

FIG. 1 is an illustrative front, left isometric view of a laundry cart plastic disposable liner showing my new design;

FIG. 2 is an illustrative front elevational view thereof;

FIG. 3 is a front, left isometric view thereof;

FIG. 4 is a front elevational view thereof;

FIG. 5 is a top plan view thereof;

FIG. 6 is an end view thereof, the other end being the same; and,

FIG. 7 is a bottom view thereof.

The broken line showing of a cart in FIGS. 1 and 2 is included for the purpose of illustrating environment and forms no part of the claimed design.
